REINFORCED CONCRETE STRUCTURE

Otto Schaub, Biel, Switzerland

Application July 21, 1933, Serial No. 681,594
In Switzerland July 30, 1932

4 Claims. (Cl. 72—61)

The invention relates to reinforced concrete structures comprising a concrete slab supported by section irons.

In reinforced concrete structures, for instance in ceilings, it is known to utilize iron reinforcement in lattice form in the concrete, whereby the lattice work, which owing to its bearing power, does away, at least partly, with the necessity of falsework or centering, prevents sliding in the concrete and ensures the transmission of the shear between the iron parts and concrete parts stressed in tension or compression respectively. With the so-called Pohlmann-ceiling these latticed girders are replaced by bulb beams which have a similar effect. The web of these beams is in places provided with apertures so that the concrete penetrating into these apertures causes an intimate connection between concrete and metal. By placing sling-like flat beams through these apertures the anchorage between the bulb beams and the concrete in its compression zone may be further increased.

The production of such anchorages being resistant to shearing is in many cases very tedious and expensive. The present invention has for its purpose to simplify such structures. According to the invention at least one metal rod bent in more than one direction is welded to the upper flange of the section girder and is embedded in the concrete plate.

A plurality of metal rods may thus be welded and the rods may be bent to a sinuous or coiled shape.

Several constructional examples of the subject matter of the invention are illustrated in the accompanying drawing, in which

Figs. 1 and 2 show in a cross-section and in a longitudinal section respectively a first constructional example.

Figs. 3 and 4 are a cross-section and a longitudinal section of a second constructional example, and

Figs. 5 and 6 similar sections of a third constructional example.

In the constructional example according to Figs. 1 and 2 I-beams *a* are used as reinforcement for a ceiling needing no falsework. On the upper flange of this section-beam two sinuous rods *b* of circular cross-section are welded staggered to each other and are embedded in the concrete slab *c* and cause thereby a connection between beam and concrete which resists shear.

The ceiling illustrated in Figs. 3 and 4 also comprises girders in the form of I-beams *a* to each of which only one sinuous shearing rod *b*

is fixed, the waves of the latter being alternately inclined by a certain angle to one or the other side of the vertical centre plane, in order to obtain a better distribution of the shearing forces in the concrete slab *c* and to prevent eventual cracking of the latter owing to excessive shearing stresses. In order to increase the effective metal reinforcement cross-section in the zone of tension a flat metal plate *d* may be welded to the lower flange of the I-beam *a*. 10

The third embodiment of the invention shown in Figs. 5 and 6 differs from the two constructional examples described above by the helical rod *b* welded to the upper flange of the I-beam *a*.

The different shaped rods bite into the concrete slab *c* and form together with the latter a rigid anchorage. These shear rods are adapted to prevent mutual displacements or distortions between the section-beam and the concrete slab and to transmit the large shearing stresses occurring when the supporting structure is subjected to a bending moment. Although the section-beam girder is only in contact with the concrete slab on the upper surface of its flange the compound effect is nevertheless perfect owing to the iron rods being welded to the girders. During the construction of the ceiling and before the hardening of the concrete the section beam alone acts as supporting girder. After the hardening of the concrete the lower flange of the girder takes over the tensile stresses of the whole compound structure and flat iron plates may be welded to the underside of the girder as indicated in the second constructional example for increasing the effective cross section if the actual bending moment requires such reenforcement. 25

I claim:

1. A reinforced concrete structure of the type described, comprising in combination, a plurality of section beams having upper flanges, a concrete slab contacting with the upper flanges of said beams, a plurality of sinuous metal rods, each extending longitudinally along the upper flange of one of said beams and in contact therewith at spaced points and being embedded in the concrete slab, the sinuous shape of the rods providing a substantial extent in the direction perpendicular to the plane of the upper flanges of the beams and the rods being welded to the beams at the points of contact. 45

2. A reinforced concrete structure of the type described, comprising in combination, a plurality of section beams having flanges, a concrete slab contacting with the upper flanges of said section

beams, and a metal rod of helical shape placed against the upper flange of one of said section beams and welded thereto at the places of contact, said rod being embedded in said concrete slab.

3. A reenforced concrete structure of the type described, comprising in combination, a plurality of section beams having flanges, a concrete slab contacting with the upper flanges of said section beams, and a metal rod of vertically extending sinuous shape placed against the upper flange of one of said section beams and welded thereto at the places of contact and inclined to different

sides of the vertical central plane of said flange, said rod being embedded in said concrete slab.

4. A reenforced concrete structure of the type described, comprising in combination, a plurality of section beams having flanges, a concrete slab contacting with the upper flanges of said section beams, and two iron rods of sinuous shape arranged at a distance from each other and staggered, said rods being placed on the upper flange of one of said section beams and welded thereto at the places of contact and embedded in said concrete slab.

OTTO SCHAUB.
